CLAIM

The ornamental design for a big ear rabbit plush toy, as shown and described.

DESCRIPTION

FIG. 1 is a front, right side perspective view of a big ear rabbit plush toy, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a rear, left side perspective view thereof;

FIG. 9 is a front, right side perspective view of the big ear rabbit plush toy with ears down, showing my new design; and,

FIG. 10 is another front, right side perspective view of the big rabbit plush toy with ears covering the whole body, showing my new design.

The broken lines in the drawings depict portions of the big ear rabbit plush toy and form no part of the claimed design.
